CABLE CLAMP

Filed Dec. 16, 1925

FIG. 2.

FIG. 1.

FIG. 3.

INVENTOR

Winfred Gladstone Milne
by *Heatherton Haughold*
Attest.

UNITED STATES PATENT OFFICE.

WINFORD GLADSTONE MILNE, OF HAMILTON, ONTARIO, CANADA, ASSIGNOR TO THE
N. SLATER COMPANY, LIMITED, OF HAMILTON, CANADA.

CABLE CLAMP.

Application filed December 16, 1925. Serial No. 75,866.

To all whom it may concern:

Be it known that I, WINFORD GLADSTONE MILNE, a subject of the King of Great Britain, and a resident of the city of Hamilton, in the county of Wentworth, Province of Ontario, Dominion of Canada, have invented certain new and useful Improvements in Cable Clamps, of which the following is a specification.

10 My invention relates to improvements in cable clamps and the object of the invention is to provide an improved form of clamp which will provide an extremely secure and efficient grip upon the cable and in which 15 the compression upon the cable will be uniformly distributed and will be more truly radial thus eliminating more perfectly the tendency to distort or crush the cable out of its normal form; a further object is to distribute the compression upon the cable from a minimum at the mouth of the clamp where the tension in the cable is a maximum to a maximum at a point where the tension in the cable is a minimum.

20 Other objects will appear in the course of the following specification.

My invention consists in the construction and arrangement of parts, all as hereinafter more particularly described and illustrated 30 in the accompanying drawings in which:—

Fig. 1 is a side view of a cable clamp embodying my improved construction showing two portions of cable connected thereby.

Fig. 2 is a transverse section (to an enlarged scale) taken on the lines 2—2 of Figs. 1 and 3.

Fig. 3 is a central longitudinal section through Fig. 1 the section being on the line 3—3 of Fig. 2.

40 In the drawings like characters of reference indicate corresponding parts in the various views.

In the form illustrated, my invention consists of a cable clamp comprising a bottom 45 plate 1 the central portion of which is depressed at 2 to form a longitudinal cable receiving depression 3 and the side edges of which are bent upwardly to form stiffening ribs 4.

50 Two portions of cable connected by my clamp are indicated by the numerals 5—5 and the portions of the cable within the clamp are enclosed by a metallic piece 6.

Opposed side plates 7 co-operate with the 55 bottom plate and their outer lateral extrem-

ities rest freely upon the bottom plate at 8.

The inner lateral extremities of the side plates 7 are of arcuate shape at 9 and the inner concave portions of these arcuate portions engage the periphery of the piece 6.

A keeper plate 10 is mounted above the side plates 7 and has formed centrally in its under face a recess 11 extending longitudinally thereof.

The side edges of this recess are indicated by the numerals 12—12.

U-bolts 13 are used for securing the clamp and the arms of these bolts extend upwardly on either side of the cable through orifices 14 in the bottom plate 1, orifices 15 in the side plates 7 and orifices 16 in the keeper plate 10.

Nuts 17 are mounted on the extremities of the bolt arms and engage the upper face of the keeper plate 10.

A number of these U-bolts are used and they are spaced apart longitudinally of the clamp.

This longitudinal spacing of the bolts diminishes from a maximum at the mouth of the clamp at "a" to a minimum at "b" adjacent to the inner end of the cable, the purpose of which will be explained hereinafter.

The construction and operation of my improved clamp is as follows:—

The end portions of each cable 5 to be gripped within the clamp may be enclosed by a strip 6 and for purposes of description this strip may be considered as part of the cable.

The U-bolts are passed upwardly through the orifices 14 in the bottom plate 1 so that the arms of each bolt lie on opposite sides of the depression 3.

The cable ends are then placed within the depression 3 and the opposed side plates 7 are placed in position with the bolts extending through the orifices 15.

The side plates lie in an inclined position with their outer edges resting freely upon the bottom plate at 8 and their inner arcuate portions 9 resting upon portions of the periphery of the cable.

The keeper plate 10 is then mounted so that the bolt arms pass through the orifices 16 therein.

The keeper plate takes a position with the upper ends of the arcuate portions 9 lying within the recess 11 in the under face of the

keeper plate and the side edges of this recess make line contact with the convex surfaces of the arcuate portions 9 at 12 which line of contact is intermediately of the length 5 of said arcs.

From an examination of Fig. 2 it will be noted that the arcuate portions 9 of the opposed side plates 7 are spaced apart to provide a gap "c" therebetween and due to the 10 inclined position of the side plates gaps are provided at "d" between the side plates and the bottom plate.

In tightening down the nuts 17 the first 15 action is to close the opposed side plates 7 down against the bottom plate at 8 due to the coefficient of friction at 12. Line contacts are thus made at 8 and 12 and surface contacts of the concave faces of the arcuate portions 9 of the periphery of the strips 20 6 which is the same as with the cable. This leaves gaps at *c* and *d*.

In this way the cable is gripped between the arcuate portions 9 and the depressed portion 3 of the bottom plate.

25 During further tightening of the nuts 17 the contacts at 12 are fixed except as regards sliding outwardly upon the flat surface of the bottom plate 1 so that during this further tightening the contacts 12 slide downwardly over the convex surfaces of the arcuate portions 9 and the side plates 7 close radially inward upon the cable reducing the gaps at "c" and "d".

Since the orifices 15 in the side plates 7 25 are of somewhat greater diameter than the bolts 13 these side plates have sufficient freedom of movement upon the bolts to permit this free movement as described.

By so constructing the parts that the 40 straight line joining the center of the bolt hole at the upper face of the keeper plate to the center of the cable passes approximately through the contact 12, the keeper plate is practically relieved of bending moment tending to bow the sides thereof downwardly.

In actual test the keeper plate bent upwardly at the sides instead of downwardly as would be expected.

50 In my improved clamp it will thus be seen that practically a truly radial compression is placed upon the cable so that there is not the usual tendency to flatten or distort the cable out of its normal round shape as is ordinarily the case when the compression is in a transverse direction.

It is desirable in clamps used on cables carrying tension and particularly in cables made of aluminum that the product of the tensile and compressive load be kept below the flow point of the cable.

60 Referring now to Fig. 3 the tensile load in the cable at "E" is 100% or a maximum, while the tensile load in the cable at "b" is 65 zero or a minimum.

It is therefore desirable that the compression in the cable caused by the clamp be a minimum at the mouth of the clamp and that it gradually increases to a maximum at "b".

70 This may be accomplished by gradually decreasing the bolt spacing from "a" to "b" so that as the tension in the cable decreases the compression increases so that the combined product of the tension by compression is kept below the flow point of the cable material and the compression in the cable at the mouth of the clamp is kept at a minimum value which is desirable.

75 From the foregoing it will be apparent 80 that I have devised valuable improvements in cable clamps of the class described whereby the objects of my invention have been attained.

85 Various modifications may be made in my invention without departing from the spirit thereof or scope of the claims and therefore the exact forms shown are to be taken as illustrative only and not in a limiting sense and I desire that only such limitations 90 shall be placed thereon as are imposed by the prior art or are specifically set forth in the appended claims.

95 What I claim as my invention is:

1. In a cable clamp of the class described, 100 the combination with a cable, of a clamp therefor comprising, a bottom plate the central portion of which is depressed to form a longitudinal cable receiving depression, a keeper plate above the bottom plate and cable, opposed side plates interposed between the bottom plate and keeper plate and each formed with an arcuate portion engaging a portion of the cable periphery, and means 105 co-acting between the bottom plate and keeper plate for forcing the side plates towards the bottom plate to grip the cable between the bottom plate and the arcuate portions of the side plates.

110 2. In a cable clamp of the class described, 115 the combination with a cable, of a clamp therefor comprising, a bottom plate the central portion of which is depressed to form a longitudinal cable receiving depression, a keeper plate above the bottom plate and cable, opposed side plates interposed between the bottom plate and keeper plate and each formed with an arcuate portion engaging a portion of the cable periphery, and means 120 co-acting between the bottom plate and keeper plate for forcing the side plates towards the bottom plate and towards each other to grip the cable between the bottom plate and the arcuate portions of the side plates.

125 3. In a cable clamp of the class described, 130 the combination with a cable, of a clamp therefor comprising, a bottom plate the central portion of which is depressed to form a longitudinal cable receiving depression,

opposed side plates, the outer lateral extremities of which rest upon the bottom plate and the inner lateral extremities of which are of arcuate shape, the concave surfaces of said

5 of arcuate shape, the concave surfaces of said
arcuate portions engaging portions of the
periphery of the cable, a keeper plate, said
keeper plate having line contact with the
convex surfaces of said arcuate portions, a
10 U-bolt, the arms of which extend upwardly
on either side of the cable through orifices in
the bottom plate, side plates and keeper
plate, the central branch of said U-bolt en-
gaging the under face of said depressed por-
15 tion of the bottom plate, and nuts on the ex-
tremities of the bolt arms and engaging the
upper face of said keeper plate.

4. In a cable clamp of the class described, the combination with the cable, of a clamp therefor comprising, a bottom plate the central portion of which is depressed to form a longitudinal cable receiving depression, opposed side plates the outer lateral extremities of which freely rest upon the bottom plate and the inner lateral extremities of which are of arcuate shape and are spaced apart, the concave surfaces of said arcuate portions engaging portions of the periphery of the cable, a keeper plate, said keeper plate having line contact with the convex surfaces of said arcuate portions, a **U**-bolt, the arms of which extend upwardly on either side of the cable through orifices in the bottom plate, side plates and keeper plate, the orifices in the side plates being of somewhat greater diameter than the **U**-bolt whereby the side plates have a certain freedom of movement upon said bolt, the central branch of said **U**-bolt engaging the under face of said depressed portion of the bottom plate, and nuts on the extremities of the bolt arms and engaging the upper face of said keeper plate.

5. In a cable clamp of the class described, the combination with a cable, of a clamp therefor comprising, a bottom plate the central portion of which is depressed to form a longitudinal cable receiving depression, opposed side plates the outer lateral extremities of which freely rest upon the bottom plate and the inner lateral extremities of which are of arcuate shape and are spaced apart, the concave surfaces of said arcuate portions engaging portions of the periphery of the cable, a keeper plate having a central longitudinal recess in its under side, the edges of said recess having line contact with the convex surfaces of said arcuate portions of the side plates intermediately thereof, a **U**-bolt, the arms of which extend upwardly on either side of the cable through orifices in the bottom plate, side plates and keeper plate, the orifices in the side plates being of somewhat greater diameter than the **U**-bolt whereby the side plates have a certain freedom of movement upon said bolt, the central branch of said **U**-bolt engaging the under face of

said depressed portion of the bottom plate, and nuts on the extremities of the bolt arms and engaging the upper face of the keeper plate.

6. In a cable clamp of the class described, 70
the combination with a cable, of a clamp
therefor comprising, a bottom plate, the cen-
tral portion of which is depressed to form
a longitudinal cable receiving depression,
opposed side plates, the outer lateral ex- 75
tremities of which freely rest upon the
bottom plate and the inner lateral extremi-
ties of which are of arcuate shape and are
spaced apart, the concave surfaces of said
arcuate portions engaging portions of the 80
periphery of the cable, a keeper plate, said
keeper plate having line contact with the
convex surfaces of said arcuate portions in-
termittently thereof, a U-bolt the arms of 85
which extend upwardly on either side of
the cable through orifices in the bottom
plate, side plates and keeper plate, the ori-
fices in the side plates being of somewhat
greater diameter than the U-bolt whereby
the side plates have a certain freedom of 90
movement upon said bolt, the central branch
of the U-bolt engaging the under face of
the depressed portion of the bottom plate,
and nuts on the extremities of the bolt arms
and engaging the upper face of the keeper 95
plate, the parts so formed that a straight
line joining the center of the bolt at the
upper face of the keeper plate and the
center of the cable approximately passes
through the point of contact of the keeper 100
plate with the arcuate portion of the cor-
responding side plate.

7. In a cable clamp of the class described, the combination with a cable, of a clamp therefor comprising, a bottom plate the central portion of which is depressed to form a longitudinal cable receiving depression, and the sides of which are bent to form longitudinal stiffening ribs, opposed side plates the outer lateral extremities of which freely rest upon the bottom plate and the inner lateral extremities of which are of arcuate shape and are spaced apart, the concave surfaces of said arcuate portions engaging portions of the periphery of the cable, a keeper plate having a central longitudinal recess in its under side, the edges of said recess having line contact with the convex surfaces of said arcuate portions of the side plates intermediately thereof, a U-bolt, the arms of which extend upwardly on either side of the cable through orifices in the bottom plate, side plates and keeper plate, the orifices in the side plates being of somewhat greater diameter than the U-bolt whereby the side plates have a certain freedom of movement upon said bolt, the central branch of said U-bolt engaging the under face of said depressed portion of the bottom plate, and nuts on the extremities of the

bolt arms and engaging the upper face of the keeper plate.

8. In a cable clamp of the class described, the combination with a cable, of a clamp therefor comprising, a bottom plate the central portion of which is depressed to form a longitudinal cable receiving depression, opposed side plates, the outer lateral extremities of which rest upon the bottom plate and the inner lateral extremities of which are of arcuate shape, the concave surfaces of said arcuate portions engaging portions of the periphery of the cable, a keeper

plate, said keeper plate having line contact with the convex surfaces of said arcuate portions, a plurality of longitudinally spaced apart U-bolts, the arms of which extend upwardly on either side of the cable through orifices in the bottom plate, side plates and keeper plate, the central branches of said U-bolts engaging the under face of said depressed portion of the bottom plate, the longitudinal spacing of the bolts gradually diminishing measured inwardly from the mouth of the clamp. 15

WINFORD GLADSTONE MILNE. 20
